The schedule referred to in the Letters Patent and making part of the same.

Dec. 1787

To all whom it may concern:

Be it known that I, Henry G. Thompson,
of the City, County and State of New York, have invented or produced
a new and original Design for a Pattern to be wrought into two ply
Ingrain and other carpeting, in colors similar to those painted
on the drawings accompanying this specification or other colors substituted in the place of those
painted on the drawings herunter; and I do hereby declare that the drawings accompany-
ing this specification do give and convey to any one skilled
in the art of Carpet weaving a more distinct and thorough descrip-
tion of the nature of my invention than it is in the power of language
otherwise to convey, and is sufficient to enable any one skilled in the art
of carpet weaving to resume my invention.

What I claim as my invention, and desire
to secure by Letters Patent, is the configuration of the Design herunter
named, when made by being wrought into two ply Ingrain or
other Carpeting, in the form similar to the drawings accompany-
ing this specification.
